UNITED STATES PATENT OFFICE.

WILLIAM MCFALLS DE WITT, OF ELKHART, INDIANA.

HAYRACK.

1,355,945.

Specification of Letters Patent.

Patented Oct. 19, 1920.

Application filed March 16, 1920. Serial No. 366,316.

To all whom it may concern:

Be it known that I, WILLIAM M. DE WITT, a citizen of the United States, and a resident of Elkhart, in the county of Elkhart and

5 State of Indiana, have invented certain new and useful Improvements in Hayracks, of which the following is a specification.

My invention is an improvement in hay racks, and has for its object to provide a 10 rack of the character specified, having fastened at the center thereof an auxiliary rack hinged to the main rack to tip forwardly to carry the rear part of the load to the front part of the main rack.

15 In the drawings:—

Figure 1 is a side view of the improved rack,

Fig. 2 is a front view.

In the present embodiment of the invention, a main rack is shown, comprising a body portion 1 having at the rear thereof supports or uprights 2 for holding the hay, and having at the front thereof the usual ladder 3. This rack is supported by the 20 running gear of a wagon, indicated at 4 in the usual manner, and an auxiliary rack is arranged at the rear of the main rack covering about half of the length of the main rack.

This auxiliary rack as shown, consists of 25 a bottom member 5 and a front member 6 extending at a right angle with respect to each other and connected and braced by inclined braces 7. The front of the auxiliary rack is an open frame-work as shown in Fig. 2, and the bottom is similarly constructed, both being formed from longitudinally extending plates having cross plates secured thereto.

The auxiliary rack is hinged at the junction 30 between the front and bottom, as indicated at 8, to the main rack 1 in such manner that it may tip forwardly with the front member 6 of the auxiliary rack resting on the body of the main rack, or may occupy 35 its normal position with the bottom 5 of the auxiliary rack resting on the bottom of the main rack.

In order to tilt the rack, I provide eyes 9 at the corners of the front 6 of the rack, 40 and to these eyes I connect flexible members

10, as for instance, ropes. The flexible members extend forwardly to a connection with a ring 11 which in turn is connected with the hook of a double block 12.

A second block 13 is connected to an eye 14 at the front of the body of the main rack, and a rope or cable 15 is threaded through the blocks in the usual manner, one end of the rope or cable being connected to the block 12, as indicated at 16 in Fig. 1. 55 60

The other end of the rope winds upon a reel 17 which is held on a shaft 18 journaled in bearings 19 on a support 20 depending from the front of the body of the main rack. This shaft 18 is provided with a crank 21 65 at its outer end by means of which it may be turned.

In operation, after this auxiliary rack has been loaded while in its position on the rear end of the main rack, the reel is turned to 70 wind up the cable. The auxiliary rack will be pulled forwardly as clearly indicated in dotted lines in Fig. 1, bringing the rear portion of the load to the front portion of the rack. After the rear portion of the load in 75 the auxiliary rack has been tilted to a position on the front end of the main rack, the rear end of the main rack is then empty and ready to be loaded in the regular way. It will be understood that other means might 80 be provided for tilting if desired or found advisable.

I claim:—

1. A rack comprising a main rack and an auxiliary rack hinged to the main rack at 85 approximately the center thereof to tilt forwardly to bring the rear portion of the load to the front of the main rack, and means for tilting said auxiliary rack, said auxiliary rack comprising a front wall and a bottom wall rigidly connected and braced against each other, said auxiliary rack being hinged to the main rack at the junction of the two walls of the auxiliary rack.

2. A rack comprising a main rack and an auxiliary rack hinged to the main rack at 95 approximately the center thereof to tilt forwardly to bring the rear portion of the load to the front of the main rack, and means for tilting said auxiliary rack, said tilting 100

means comprising a reel at the front of the main rack and a block and tackle arranged between the main rack and the top of the front wall of the auxiliary rack and connected with the reel.

3. A rack comprising a main rack and an auxiliary rack hinged to the main rack at approximately the center thereof to tilt forwardly to bring the back portion of the load

10 to the front of the main rack and normally resting upon the main rack to receive and

hold a portion of the load, and means for tilting said auxiliary rack.

4. A hay rack, comprising a main rack and an auxiliary rack hinged to the main 15 rack at approximately the center thereof, and designed to carry approximately half the load and to tilt toward the opposite half of the load, and means for tilting the auxiliary rack.

WILLIAM McFALLS DE WITT.
